UNITED STATES PATENT OFFICE

153,183

DESIGN FOR A TABLECLOTH OR SIMILAR ARTICLE

George Sklar, Philadelphia, Pa.

Application February 28, 1948, Serial No. 144,811

Term of patent 3½ years

(Cl. D92—26)

To all whom it may concern:

Be it known that I, George Sklar, a citizen of the United States of America, residing in Philadelphia, county of Philadelphia, and State of Pennsylvania, have invented a new, original, and ornamental Design for a Tablecloth or Similar Article, of which the following is a specification, reference being had to the accompanying drawing, forming part thereof, wherein the figure is a plan view of a tablecloth showing my new design.

I claim:

The ornamental design for a tablecloth or similar article, substantially as shown.

GEORGE SKLAR.
